UNITED STATES PATENT OFFICE.

GEORGE G. GUY, OF BATAVIA, ILLINOIS, ASSIGNOR TO THE UNITED STATES WIND ENGINE AND PUMP COMPANY, OF SAME PLACE.

PUMP.

SPECIFICATION forming part of Letters Patent No. 657,102, dated September 4, 1900.

Application filed October 6, 1898. Serial No. 692,839. (No model.)

To all whom it may concern:

Be it known that I, GEORGE G. GUY, a citizen of the United States, residing at Batavia, in the county of Kane and State of Illinois, 5 have invented certain new and useful Improvements in Pumps, of which the following is a specification.

My invention relates to certain new and useful improvements in pumps intended primarily for tubular wells, but which may be employed in any variety of pumps desired.

My invention relates first to an improved strainer adapted to be attached to the bottom of a pump, especially in tubular wells, to prevent the entrance of gravel, &c., and is designed to produce a strainer that will be effective in operation, adjustable to any desired capacity, and which can be cheaply and easily constructed.

20 To this end I construct my strainer of annular sections having notched edges which can be readily cast and which when united form a cylindrical strainer whose capacity may be varied as desired by increasing or diminishing the number of annuli employed.

25 My invention further relates to the construction and mounting of the lower valve in the dome, whereby I am enabled to secure the valve in place without forming any projections on the outside of the dome or increasing its size, so as to necessitate the boring of a well of larger diameter than the exterior diameter of the dome.

Referring to the accompanying sheet of drawings, in which the same letters of reference are used to designate identical parts in all the views, Figure 1 is an elevation of my invention showing the dome and strainer in position. Fig. 2 is a section on the line 2 of Fig. 1. Fig. 3 is a top plan view of the bottom valve and its seat. Fig. 4 is a section on the line 4 of Fig. 3. Fig. 5 is an inverted perspective of one of the annuli composing the strainer, and Fig. 6 is a top plan view of 40 the modified annulus forming the bottom of the strainer.

45 A represents the dome, which is of a generally-cylindrical shape somewhat contracted at its upper end and which is interiorly screw-threaded to receive the tubing. Extending diametrically across the upper portion of the

dome is the cross-piece A', which has a central aperture which is interiorly screw-threaded to receive the bolt B. The function of this cross-piece A' is to furnish means of attaching the spider C, carrying the lower valve or valves D, to the dome without the employment of exterior lugs, as has been heretofore customary.

55 The spider C consists of the annulus and the cross-piece C', which is similar to the cross-piece A' and is similarly connected to the bolt B. The annular portion of the spider is contracted on its upper side, which contracted portion forms a shoulder C², upon which the lower end of the dome A is seated, the leather washer D' being interposed to make a fluid-tight joint.

60 The valves D are conveniently constructed of a leather disk D², secured to the cross-piece C' by the screws D³ and having the substantially-semicircular metallic pieces D⁴ secured to the upper side thereof by the screws D³ to give the valve the necessary weight and stiffness.

65 The spider C is secured in position by the bolt B, which has the nuts B' and B² located above the cross-pieces A' and C', respectively. If no strainer is employed, I would employ a nut or nuts on the lower side of the cross-piece C'; but in the form shown with the strainer I employ the double-threaded connecting-nut B³, as hereinafter described.

70 The strainer E is composed of a series of annuli E', one of which is shown in perspective in Fig. 5. These annuli have the inner ring e, which has formed integral therewith the outer ring e', which has the deep notches e² therein. The inner and outer rings overlap, so as to form imbricated joints, as shown 75 in Fig. 2. The notched edge of the uppermost annulus E' takes into the interior shoulder C², formed in the lower side of the spider C. The lowermost annulus E² differs from the others in that it does not have the inner ring e, but a perforated web e³, forming the bottom of the strainer. The bolt B⁴, secured in the connecting-nut B³, passes through the centrally-located aperture e⁴ in the lowermost annulus or disk E², and the nuts B⁵, co-operating therewith serve to secure the various annuli together, so as to make a

practically rigid strainer with a large number of small perforations. The objects in constructing the strainer of annuli are to make a construction that can be readily cast, which would be hard to do if it were integral, and to make a strainer that can be readily adjusted to any size desired.

While I have shown my invention as embodied in the form which I at present consider best adapted to secure the advantages thereof, it will be understood that it is capable of some modifications and that I do not desire to be limited to the exact form shown and described; but

15 What I claim as new, and desire to secure by Letters Patent of the United States, is—

1. A strainer for pumps, &c., composed of the dome A the spider C for the valve-seat secured to the under side of the dome A, the 20 disk E² beneath said spider, the overlapping annuli E' having the notches e² in the edges deeper than the overlapping portion, all these parts overlapped and coöperating to form a rigid perforated tube of which the dome A is 25 the top and the disk E² the bottom, and rigid connections between the spider C and the disk E², substantially as shown and described.

2. A strainer for pumps, &c., composed of a dome the spider for the valve-seat secured 30 to the under side of the dome, the spider forming the upper end of the tube, with the disk forming the lower end of the tube, the

annuli having their edges notched substantially as shown and interposed between the spider and the disk, all the parts overlapped 35 and coöperating to form a rigid perforated tube, and the bolt connecting the spider and the disk and clamping the annuli in place.

3. In a pump, the combination of the dome A having the cross-piece A² therein, with the 40 valve-spider C having the shoulder C² upon its upper side forming a seat for the dome and the interior shoulder C³ on its lower side forming a seat for the uppermost annulus E', the annuli E' coöperating to form a perforated cylinder, and bolts for connecting the spider to the dome and to the annuli, substantially as shown and described.

4. In a pump, the combination of the dome A having the cross-piece A² therein, with the 45 valve-spider C having the shoulder C² upon its upper side forming a seat for the dome and the interior shoulder C³ on its lower side forming a seat for the uppermost annulus E', the annuli E' coöperating to form a perforated cylinder, a perforated disk E² forming the bottom of said cylinder, and bolts for connecting the spider with the cross-piece A² and the disk E², substantially as and for the purpose described. 55
